[57] CLAIM

The ornamental design for a guitar body and neck, as
shown and described.

DESCRIPTION

FIG. 1 is a top, front and left side perspective view of a
guitar body and neck showing our new design;

FIG. 2 is a bottom plan view thereof;

FIG. 3 is a rear elevational view thereof, shown with
the leg rest in an open position;

FIG. 4 is a left side elevational view thereof; and

FIG. 5 is a right side elevational view thereof.

FIG. 1

FIG. 2

FIG. 3

FIG. 4

FIG. 5
